UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

LOOP RETAINER FOR SEWING MACHINES.

Application filed April 27, 1925. Serial No. 26,109.

The invention relates to new and useful improvements in loop retainers for sewing machines, and more particularly to a loop retainer used for holding the needle thread loops back on the looper in a multiple thread sewing machine, wherein a single looper cooperates with a plurality of needles.

An object of the invention is to provide a loop retainer which is not only movable over the upper face of the looper, but also longitudinally of the looper to aid in positioning and holding back certain of the needle thread loops on the looper so as to insure that the needles will enter their respective thread triangles in the forming of the stitches.

A further object of the invention is to provide loop retainers which derive their movement from a feeding mechanism, which provides a very compact mechanism which may be readily used in a cylinder bed machine, where the tubular articles are formed and fed off from the end of the arm.

These and other objects will in part be obvious and will in part be hereinafter more fully disclosed.

In the drawings which show by way of illustration one embodiment of the invention—

30 Figure 1 is a view partly in section and partly in side elevation of a portion of a sewing machine embodying my invention;

Fig. 2 is a sectional view on the line 2—2 of Fig. 1;

35 Fig. 3 is a plan view of a portion of the work supporting arm with portions of the feeding mechanism removed so as to show the loop retainers and the manner of operating the same;

40 Fig. 4 is a detail in section showing the needles, the looper, the end of the feed bar and the loop retainers and the means for supporting and operating the same; the section is on the line 4—4 of Fig. 5;

45 Fig. 5 is a plan view with the parts shown in Fig. 4, with the needles and looper position as shown in said figure;

50 Fig. 6 is a view similar to Fig. 4, but with the looper at the forward end of its stroke, the feed bar raised, and the loop retainers at the right-hand end of their movement, but not yet moved across the looper, the section in this figure is on the line 6—6 of Fig. 7, and

Fig. 7 is a plan view of the parts as positioned in Fig. 6.

The invention has to do broadly with loop retainers for a multiple needle machine, and preferably a three-needle machine, set abreast, and with which a single thread carrying looper cooperates. This looper moves forward into the needle thread loops one after another. It is then moved laterally for its needle avoiding movement, and the needles enter their respective triangles.

Referring to the needles as needle No. 1, which is next to the looper eye when the looper is at the forward end of its stroke; the middle needle as No. 2, and the other needle as No. 3. Needle No. 1 should pass between the thread triangle formed by the loop of this needle on the looper and the thread of the looper extending from the eye to the previous concatenation of the needle thread loops and looper thread. Needle No. 2 should pass with certainty between its own needle thread loop on the looper, and the thread of the looper running from the eye thereof to the previous concatenation of the threads, and also in rear of the needle thread loop of needle No. 1. Needle No. 3, should pass in front of its own needle thread loop on the looper, and in rear of the needle thread loop of needle No. 2. It is well known that these needle thread loops on the looper, when the looper is retracted, are dragged by the looper rearwardly, but there is no positive way of keeping the needle thread loop on the looper separated. Prior to my invention, loop retainers have been provided for holding these needle thread loops separated. One instance is shown in the patent to Karl Maier #1,098,814, granted June 2, 1914.

The present invention has to do with an improvement in the manner of mounting loop retainers of the type shown in this Maier patent, so as to enable the loop retainer to be used in connection with a cylinder machine, and so as to enable the retainers to operate to further separate the needle thread loops so as to give ample clearance space for the needles to enter their respective thread triangles even though the needles be set very closely together. The loop retainers are given four movements—one, a movement forward across the looper, then a movement rearwardly of the looper, that is, toward the heel of the looper, which carries the needle thread loops

engaged thereby backward on the looper to a certain extent, and then a movement to a position where the needle thread loops may pass the loop retainers, and finally, a movement in a direction forward of the looper to its initial position for its next cycle of movement. This loop retainer consists of an arm or bracket carrying fingers or projections which cooperate with the respective needle thread loops engaged thereby. This arm or bar is carried by a sleeve mounted to swing about an axis on which the looper oscillates as it moves into and out of the needle thread loops. This sleeve also moves endwise of its support, and thus the four motions are imparted thereto. The oscillating movement of the sleeve carries the fingers backward and forwardly longitudinally of the looper, and the endwise movement of the sleeve carries said fingers across the looper and retracts it to a position clear of the looper. This sleeve is moved by the arm which is connected with the feed bar. The up and down movements of the feed bar moving the feed dog into and out of engagement with the fabric, oscillate the sleeve, and the endwise movement of the feed bar moves the sleeve endwise on its support.

Referring more in detail to the drawings, my improved loop retainers are shown as applied to a feed-off-the-arm machine which includes a work supporting cylinder arm 1 in which is mounted a looper supporting shaft 2. Above the looper supporting shaft 2 is a feed bar 3 which is provided with a main feed dog 4 and a differential feed dog 5. The feed bar 3 is moved endwise of the work supporting arm for imparting feed movements to the feed dogs, and it is raised and lowered in the arm for moving the feed dogs into and out of engagement with the fabric. The feeding mechanism is in general of the type shown in the patent to Joseph Berger #1,312,823, granted August 12, 1919, and further description thereof is not thought necessary. Co-operating with these feed dogs is a presser foot 6 carried by a presser bar 7. The machine may be equipped with trimming devices for trimming the fabric edges, which fabric edges are adapted to be abutted or overlapped and joined by a flat seam as disclosed in said patent. To this end, the machine is provided with a reciprocating needle bar 8 carrying three needles 9, 10 and 11. These needles are set abreast, that is, in a plane at right angles to the line of feed, and co-operating with all three needles beneath the throat plate indicated at 12 is a thread carrying looper 13. This thread carrying looper 13 is mounted on the looper supporting shaft 2 and as the shaft oscillates, it will move the looper, first into the needle thread loop of the needle 9, then into the thread loop of the needle 10, and then into the thread loop of the needle 11, so that all three needle loops

are engaged by this one looper. This is clearly shown in Figure 4 and 6 of the drawings. The looper as it is retracted is moved laterally as indicated in Fig. 5 of the drawings, so that the needles on their downward movement, will pass on the other side of the looper. The feed is off the end of the arm, and therefore, the thread of the looper running from the eye thereof, and to the previous concatenation of the thread loops, will extend toward the end of the arm. The needle thread loops on the looper will have their shanks also extending toward the end of the work supporting arm. In Figures 4 and 6 of the drawings, I have shown diagrammatically the needle thread loops on the looper. In Fig. 6, the looper is at the forward end of its stroke; while in Figures 4 and 5, the looper has been retracted and the retainers forming the present invention have engaged the two left-hand needle loops, and pushed them back on the looper. The looper thread is indicated at 14. The needle thread loop of the needle 9 is indicated at 15; the needle thread loop of the needle 10 at 16; and the needle thread loop of the needle 11 at 17. The needle thread loop 17 will be properly held back on the looper by reason of the fact that the looper adjacent its eye is wider or larger than farther back on the looper, and while the loop may slip forward on the looper as it is retracted, it will be dragged back sufficiently so that the needle 11 will with surety pass in front of the needle thread loop 17, and into the triangle formed by this needle thread loop 17, the body of the looper and the looper thread 14 (see Fig. 5).

In order to hold the loops 15 and 16 back on the looper, and to further crowd them back to a certain extent so that they will be properly spaced from each other and from the needle thread loop 17, I have provided two loop retainers 18 and 19. The loop retainer 18 as clearly shown in Figures 4 and 5 of the drawings, is in front of the needle thread loop 15, and deflecting or crowding the same rearward on the looper, and thus opening wide the triangle formed by this needle thread 18, the body of the looper, and the looper thread 14. Likewise, the retainer 19 engages a needle thread loop 16, and holds the same back on the looper and well away from the needle thread loop 17, so that the needle 10 will with certainty enter its triangle formed by the needle thread loop 16, the body of the looper, and the looper thread 14. The two retainers 18 and 19 also hold the thread loops 15 and 16 properly spaced from each other, so that the needle 9 will pass between these needle thread loops 15 and 16. This insures a perfectly concatenated three-needle flat seam, wherein the needle thread loops are all locked by a single looper thread.

In order to impart to these retainers 18

and 19 their proper movements, said retainers or fingers are carried by a member 20 which is integral with an arm 21 carried by a sleeve 22. The arm 21 is bent laterally at its upper end to form the member 20, and at the outer end of this arm, are the retainer fingers 18 and 19. The sleeve 22 is mounted on the looper supporting shaft 2, and is free to oscillate thereon, and also to move endwise thereof, so that the looper supporting shaft serves merely as a support for the sleeve. The sleeve has a laterally projecting arm 23 with a ball head 24 on the end thereof. Mounted on the end of the main feed bar 3 is a bracket arm 25. Said arm extends laterally of the feed bar, and thence downwardly to a position at one side of the looper supporting shaft 2. Said bracket arm at its lower end has a recess which receives the ball 24. This bracket arm 25 moves with the feed bar, and therefore, it has a movement backward and forward in a direction lengthwise of the work supporting arm, which is in a direction longitudinally of the looper supporting shaft, and at right angles to the plane of movement of the looper. It also has a movement up and down as the feed dog is moved into and out of engagement with the material, which is caused by the up and down movements of the end of the feed bar. The up and down movements of the feed bar, therefore, through the arm 23, will oscillate the sleeve 22, while the backward and forward movements of the feed bar, through this bracket 25 and the arm 23, will move the sleeve in an endwise direction, and this, as has been stated, causes the retainer fingers to move across the looper to a sufficient extent to engage the needle loops thereon, while the rocking of the sleeve moves the fingers toward the rear end of the looper, and this causes the fingers to engage the needle thread loops on the looper and move the same toward the rear end of the looper.

The operation of the improved loop retainers is as follows: When the looper moves into the needle thread loops, it moves forward to the end of its stroke. At this time, the looper is fully into the needle thread loops, and the needles are at the extreme upper end of their stroke. As the looper starts to retract, it begins its lateral movement, and the lateral movement of the looper is toward the arm 21, and underneath the retainer fingers 18 and 19. Just as the looper is reaching the forward end of its stroke, the feed stroke occurs and is completed. This forward movement of the feed bar moved the sleeve 22 forward on the looper supporting shaft 2, and moved the retainers 18 and 19 over the looper, so that the combined forward movement of the retainer fingers and lateral movement of the looper, moves these retainers in between the needle thread loops on the looper, as shown in Fig. 6 of the drawings. The feed dog is now lowered for its retracting movement, and the lowering of the feed dog will oscillate the sleeve 22 to the left as viewed in Fig. 4, and will move the retainers 18 and 19 toward the heel of the looper. This not only brings the retainers which were in front of the needle thread loops in Fig. 6 backward into engagement with the loops, but will also crowd the loops back on the looper, or deflect the threads between the shanks of the respective loops and the looper so as to give ample room for the needles 9 and 10 to enter their respective thread triangles as above described. During the retracting movement of the feed dog, the loop retainers are also moved therewith from between the needles, and after they are entirely clear of the needles, they are again oscillated to the right as viewed in Fig. 4, back to the position shown in Fig. 6, and this is brought about by the raising of the feed dog into engagement with the fabric.

From the above it will be noted that I have provided loop retainers which may be operated from the feeding mechanism of the machine, and that both the raising and lowering of the feed bar, as well as the endwise movement thereof, are utilized in giving the desired movements to these retainers. I have, therefore, provided not only four-motion loop retainers, that is, loop retainers which move across or over the looper, and thence rearwardly or toward the heel of the looper, when moving into engagement with the needle thread loops, and positioning the same, and which are moved backwardly from over the loopers and then forwardly to their initial starting position in their cycle of movement. Likewise, I have provided loop retainers especially adapted for a cylinder bed machine, which may be packed in the end of a cylindrical arm and operated by the feeding mechanism therein.

While I have described my improved loop retainer operating mechanism as especially adapted to be used in connection with a cylinder bed machine, it will be understood that it may, however, be used in other types of machines, such as a flat bed machine, in which case, of course, the looper would move at right angles to the line of feed, as in the present case, and the retainers would be operated in conjunction with the loopers by the up and down movement of the feed oscillating the retainers or moving them toward and from the heel of the looper, while the movement of these retainers towards and across the loopers and back therefrom would be derived from the lengthwise or feeding movements of the feed bar. While I have described the sleeve carrying the loop retainers as mounted on the looper supporting shaft, it will be understood that this is merely a convenient support for said sleeve, and said sleeve might be mounted otherwise. In

other words, the fact that the present support of the sleeve also supports the looper, does not in any way affect the function of the looper or affect the function of the loop retainers. It is merely a support for the loop retainers.

It is obvious that minor changes in the details of construction and the arrangement of the parts may be made without departing from the spirit of the invention as set forth in the appended claims.

Having thus described the invention, what I claim as new and desire to secure by Letters-Patent, is—

15. 1. In a sewing machine, the combination of a feeding mechanism including a feed bar, a feed dog carried thereby, a plurality of needles set abreast, an oscillating thread carrying looper cooperating with the needles, loop retainers, means independent of the feed bar for supporting said loop retainers, means operated by the up and down movement of the feed bar for moving said thread retainers in a plane parallel with the plane of oscillation of the looper, and means operated by the endwise movement of the feed bar for moving said retainers in a path substantially at right angles to the plane of oscillation of the looper.
20. 2. A sewing machine including in combination, a cylindrical work supporting arm, a looper supporting shaft located in said arm and extending lengthwise thereof, a looper rigidly mounted on said shaft and adapted to oscillate transversely of the work supporting arm and move laterally in said arm for a needle avoiding movement, loop retainers associated with said looper, a sleeve mounted on the looper supporting shaft carrying said retainers, said sleeve being free to oscillate and move endwise on said shaft, and devices connected to said sleeve for moving the same endwise and oscillating said sleeve for imparting movements to the retainers carried thereby for causing said retainers to engage and hold the needle thread loops on the looper spaced and positioned for the needles to pass.
25. 3. A sewing machine including in combination, a cylindrical work supporting arm, a plurality of needles set abreast and operating at the end of said work supporting arm, a looper shaft extending lengthwise thereof, a looper rigidly mounted on said shaft, a feed bar extending lengthwise of said arm, and having a back and forth and an up and down movement, a sleeve freely mounted on said looper supporting shaft, loop retainers mounted on said sleeve and cooperating with said looper, an arm extending laterally from said sleeve, a bracket arm extending laterally from said feed bar and having a depending portion connected to said arm on the sleeve whereby the back and forth movements of the feed bar impart endwise movement to the

sleeve carrying the retainers and whereby the up and down movements of the feed bar impart an oscillating movement to said sleeve.

4. A sewing machine including in combination, a cylindrical work supporting arm, a looper shaft extending lengthwise thereof, a single thread carrying looper mounted on said shaft and adapted to operate transversely of said arm and move sidewise for a needle avoiding movement, a plurality of needles with which said looper cooperates, a feed bar extending lengthwise of said work supporting arm and having a back and forth and an up and down movement, a sleeve mounted on the looper supporting shaft, loop retainers mounted on said sleeve, an arm projecting laterally from the sleeve, a bracket arm projecting laterally from the feed bar and connected to said arm whereby when said feed bar is moved endwise for feeding the material along the work supporting arm, said retainers are moved toward and across the upper face of the looper, and whereby when said feed bar is lowered, said looped retainers are moved lengthwise of the looper, and caused to engage the needle thread loops on the looper for holding the same separated and properly positioned for the needles to pass.

5. In a sewing machine, a cylindrical work supporting arm, a feed bar extending lengthwise of the arm, a feed dog carried thereby, said feed bar having a back and forth and an up and down movement for imparting four motions to the feed dog, a needle, a thread carrying looper cooperating with the needle and movable in a plane substantially at right angles to the longitudinal axis of the feed bar, a loop retainer associated with said looper, and means whereby the back and forth and up and down movements of the feed bar impart movements to the retainer lengthwise of and transversely of the looper.

6. In a sewing machine, the combination of a feeding mechanism including a feed bar adapted to be moved back and forth and raised and lowered, a feed dog carried thereby, a plurality of needles set abreast, an oscillating thread carrying looper cooperating with the needles, loop retainers, means for supporting said loop retainers whereby they may be moved in a direction substantially parallel with the path of the looper and in a direction substantially at right angles to the path of the looper, and means operated by the feed bar in its back and forth and up and down movements for imparting the movements to the retainers.

7. In a sewing machine, the combination of a feeding mechanism including a feed bar adapted to be moved back and forth and raised and lowered, a feed dog carried thereby, a plurality of needles set abreast, an oscillating thread carrying looper cooperating with the needles, loop retainers, means for supporting said looped retainers whereby they

may be moved in a direction substantially parallel with the path of the looper and in a direction substantially at right angles to the path of the looper, and means operated by the feed bar in its back and forth and up and down movements for imparting the movements to the retainers, said operating means for the retainers being timed so as to move

said retainers transversely of the looper and rearwardly of the looper for engagement with the needle loops, and thence transversely of the looper and forwardly of the looper to release said needle thread loops. ¹⁰

In testimony whereof I affix my signature.

JAMES R. MOFFATT.
